UNITED STATES PATENT OFFICE.

JACOB BERNHARD MOSES, OF DALLAS, TEXAS.

HOSE-SUPPORTER.

989,024.

Specification of Letters Patent. Patented Apr. 11, 1911.

Application filed July 26, 1909. Serial No. 509,643.

To all whom it may concern:

Be it known that I, JACOB B. MOSES, a citizen of the United States, residing at Dallas, in the county of Dallas and State of 5 Texas, have invented a new and useful Hose-Supporter, of which the following is a specification.

The objects of the invention are, generally, the provision in a merchantable form, 10 of a device of the class above described which shall be adapted to be retained upon the leg of the wearer without the use of ordinary fastening means; other and further objects being made manifest hereinafter as the description of the invention progresses.

With these and other objects in view, as hereinafter more fully described, the invention consists in the novel construction of parts hereinafter described, delineated in the 20 accompanying drawings, and particularly pointed out in that portion of this instrument wherein patentable novelty is claimed for certain peculiar and distinctive features of the device, it being understood, that, with- 25 in the scope of what hereinafter thus is claimed, changes in the form, proportions, size, and minor details of the structure may be made without departing from the spirit or sacrificing any of the advantages of the 30 invention.

Similar numerals of reference are employed to denote corresponding parts throughout the several figures of the drawings.

35 In the accompanying drawings; Figure 1 shows the invention in perspective applicance to the leg of the wearer; and Fig. 2 is a detail perspective of a portion of the device.

40 In the accompanying drawings, the numeral 1 denotes, generally, a sock, which may be of any construction and of any form. I have used the term "sock" as a generic term, and it is to be understood that the 45 same may include half-hose, full length stockings, or any other form of leg covering.

The sock is provided at its top with a longitudinally extending tab 2, rising from the 50 upper edge 11 of the sock. The tab 2 is provided at its outer lateral edge 3 and at the top, with a laterally projecting band 12 adapted to extend around the leg of the wearer. Located inside the tab at its top and at its inner lateral edge 5 is a reinforcing strip 6 connected with the adjacent por-

tion of the tab by attaching means of any sort, whereby the free end of the band may be connected with the tab. In the present instance the attaching means is shown in the form of buttons, which are sewed to the tab and to the reinforcing strip. The band 12 is provided, throughout the major portion of its length, with button-holes 8 spaced apart, the width between the buttons 7 and the button-holes 8 being such that when 60 these members are in engagement, the band 12 will be distended to its full width. The straight lateral edge 3 is adapted to be disposed upon the front of the leg of the wearer, the buttons being disposed at the inside of the leg. By this construction, the buttons are so positioned that when the outside of the leg of the wearer comes in contact with an obstacle of any sort the buttons 65 will not be driven into the leg of the wearer. 70

So far as I am advised as to the state of the art, it has been customary hitherto for the band 12 to rise directly from the upper edge 11 of the sock. By this construction a V-shaped space is allowed to intervene between the upper edge 11 of the sock and the lower edge 9 of the band and into this V-shaped opening, the flesh of the wearer is crowded causing great discomfort, notably when, as is frequently the case, the sock 80 moves circumferentially upon the leg of the wearer. This V-shaped opening I dispense with by providing the upstanding tab 2 whereby the band is spaced apart from the upper edge of the sock. 85

It is to be understood that the sock 1, the tab 2, and the band are fashioned integrally, the several members being formed in a single operation, during the manufacture of the sock. The material from which the 95 parts are commonly fashioned possesses sufficient resiliency so that the band 12 may exercise its proper function, thereby doing away with the cumbersome and irritating hose supporters now in use. 90

Having thus described my invention, what I claim as new and desire to protect by Letters Patent is:—

As a new article of manufacture, a sock and a supporting means therefor, the material of the sock at the front thereof being extended upwardly and of a width to cover the entire front of the leg, vertically spaced buttons secured to the extended portion of the sock at one upper corner thereof, and a 105 110 115

leg encircling band integral with the extended portion at the opposite upper corner, the said band being formed with vertically spaced button-holes and having its upper 5 edge coincident, throughout, with the upper edge of the extension.

In testimony that I claim the foregoing

as my own, I have hereto affixed my signature in the presence of two witnesses.

JACOB BERNHARD MOSES.
